UNITED STATES PATENT OFFICE.

HOLMES ERWIN PENN, OF MADISON, NORTH CAROLINA, ASSIGNOR TO PENN BROS. SUSPENDER COMPANY, INC., OF MADISON, NORTH CAROLINA.

GARTER.

1,170,781.

Specification of Letters Patent.

Patented Feb. 8, 1916.

Application filed September 16, 1914. Serial No. 862,095.

To all whom it may concern:

Be it known that I, HOLMES ERWIN PENN, a citizen of the United States, residing at Madison, in the county of Rockingham and State of North Carolina, have invented a new and useful Garter, of which the following is a specification.

The present invention appertains to garters or hose supporters, and aims to provide novel and improved means for attaching the ends of the elastic to the pad, whereby the tension of the elastic or band may be adjusted without the necessity of adjusting the take-up slide of the elastic, and whereby the elastic may be readily detached from the pad and substituted by a new one when the old one becomes worn or "dead".

It is also within the scope of the present invention to provide unique means for attaching the ends of the elastic or band to the pad, which means will be simple and inexpensive, as well as being convenient, practical, serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a perspective view of the garter or hose supporter. Figs. 2 and 3 are enlarged sectional views taken on the lines 2-2 and 3-3, respectively, of Fig. 1.

In carrying out the present invention, there is provided a pad 1, of approximate triangular contour, and which embodies an outer ply or facing 2 of leather or other similar material, and an inner ply or lining 3 for protecting the metallic parts from contact with the flesh, and to form a cushion adapted to fit snugly against the limb. The end portions 4 and 5 of the pad 1 are in the form of tapered tongues or flaps, having square ends, and an ordinary hose fastener or clasp 6 is attached to the lower apical portion 7 of the pad 1 to depend therefrom.

The elastic or band 8 cooperates with the pad 1 for embracing the limb, the salient fea-

tures of the present invention residing in the manner in which the ends of the elastic 8 are attached to the pad 1. One end of the elastic 8 is engaged through a flat elongated loop 9 and sewed upon itself to attach the loop 9 thereto, and the outer or exposed edge of the said loop 9 is provided with a hook 10 projecting therefrom and having its bill 11 relatively long and bent on a compound curve to snap through an eyelet 12 clenched through the leather facing 2 of the pad 1 adjacent the free end of the tongue or flap 5 of the pad. The peculiar bill 11 of the hook 10 prevents the hook 10 from being accidentally snapped out of engagement with the eyelet 12, although the hook 10 may be readily snapped into and out of engagement with the eyelet 12, by properly manipulating the parts, in order that the corresponding ends of the elastic and pad may be attached and detached whenever desired, such as for the purpose of supplanting an old or "dead" elastic by a new one. The other end of the elastic 8 is bent back to provide a loop 13, the said end of the elastic being attached to a take-up slide 14 adjustable upon the body portion of the elastic, for enabling the elastic to be adjusted to any particular size desired, as usual. An elongated flat loop 15 is engaged to the loop 13 of the elastic, and the outer edge or bar of the loop 15 is provided with a hook 16 projecting therefrom intermediate the ends of the loop 15, and the bill 17 of the hook 16 extends through approximately three fourths of a complete circle, and is relatively short as compared with the bill 11 of the hook 10, so that the bill 17 of the hook 16 may be readily engaged to and disengaged from the eyelets 18, 19 and 20 which are clenched through the leather facing 2 of the pad 1. The eyelet 18 is arranged at the free end of the tongue or flap 4 of the pad 1, while the eyelet 20 is arranged at the center of the pad 1, and the eyelet 19 is disposed intermediate and in the line extending through the eyelets 18 and 20. The series of eyelets 18, 19 and 20 thus extend from the free end of the tongue or flap 4 to the central portion of the pad 1, and are suitably spaced apart for the purposes.

In the use of a garter or hose supporter of the nature herein disclosed, there are three lines of forces, namely, one extending vertically between the fastener or clasp 6 and

the central portion of the pad 1, one extending between the central portion of the pad 1 and the end or tongue 4 of the pad 1 along the series of eyelets 18, 19 and 20, and one 5 extending between the central portion of the pad 1 and the end or tongue 5 of the pad 1 having the eyelet 12, the last two mentioned lines of forces extending between the ends of the elastic 8 and the central portion of 10 the pad, as will be apparent. Thus the lines of forces meet at the central eyelet 20, whereby the equilibrium of the pad 1 will be maintained, and the series of eyelets 18, 19 and 20 extending along the normal line 15 of force between the central portion of the pad 1 and the corresponding end of the elastic 8, will enable the hook 16 to be engaged with any one of the eyelets 18, 19 and 20, without destroying the equilibrium of 20 the pad, or altering the lines of forces. Thus, the line of force extending upward from the fastener or clasp 6 will be properly balanced or counteracted by the lines of 25 forces extending from the ends of the elastic to the central portion of the pad, notwithstanding the engagement of the hook 16 with any of the eyelets 18, 19 and 20, and whereby the pad will be held against shifting out of its place in use, as would be ob- 30 jectionable.

The hook 10 at one end of the elastic 8 is first engaged through the eyelet 12, and the bill 11 of the said hook will so engage through the eyelet 12 and between the plies 35 of the pad 1, as to prevent the accidental detachment of the hook 10 during the ordinary usage of the garter or hose supporter. Several sets of elastics may be sold with 40 each pair of pads, for the successive application of the pairs of elastics to the pads as the elastics become worn out or "dead".

With the present device, it is not necessary to adjust the take-up slide 14 of the elastic 8, whenever the tension of the elastic be- 45 comes more or less than the wearer desires, since after the take-up slide 14 has been ad- justed to the proper size desired, the hook 16 in engaging the eyelet 18 will enable the elastic and pad to comfortably embrace the 50 limb. The wearer may at any time engage the hook 16 with the successive eyelets 19 and 20 for increasing the tension of the

elastic should the same become slightly stretched after continued use. Thus, by en- gaging the hook 16 with the several eyelets 55 18, 19 and 20, the tension of the elastic 8 may be regulated as desired by the wearer, and without the necessity of continually ad- justing the take-up slide 14 of the elastic, which is not only laborious, but which also 60 tends to wear out the elastic more quickly. It is therefore only necessary to adjust the take-up slide 14, whenever the size of the elastic or band 8 is to be regulated. The bill 17 of the hook 16 is readily engageable with 65 18 and disengageable from the eyelets 18, 19 and 20 in order that the corresponding ends of the garter and pad may be readily connected or detached in applying and remov- 70 ing the garter, respectively. The tension 70 of the elastic will hold the hook 16 in en- gagement with the corresponding eyelet, when the garter is worn, so as to prevent the accidental loosening of the garter. It is to be noted that the hooks 10 and 16 be- 75 ing engageable through the respective eye- lets 12 and 18—19—20 enable the ends of the elastic to swing slightly relative to the pad for enabling the garter to readily accommo- 80 date itself to the limb.

Having thus described the invention, what is claimed as new is:—

A garter of the type described embodying an approximately triangular pad having a 85 clasp depending from its lower apical por- tion, and having a series of eyelets between the center of the pad and one end thereof, and an elastic having one end attached to the other end of the pad and having a hook at its other end engageable through said 90 eyelets, said series of eyelets being arranged in the line of strain between the pad and that end of the elastic having the hook, so that there is no tendency to destroy the equilibrium of the pad when the hook is 95 engaged through any of said eyelets.

In testimony that I claim the foregoing as my own, I have hereto affixed my signature in the presence of two witnesses.

HOLMES ERWIN PENN.
